UNITED STATES PATENT OFFICE

158,620

SACHET OR SIMILAR ARTICLE

Leon M. Share, Los Angeles, Calif.

Application August 8, 1949, Serial No. 4,364

Term of patent 3½ years

(Cl. D86—10)

To all whom it may concern:

Be it known that I, Leon M. Share, a citizen of the United States, residing in the city of Los Angeles, in the county of Los Angeles and State of California, have invented a new, original, and ornamental Design for a Sachet or Similar Article, of which the following is a specification, reference being had to the accompanying drawing, forming a part thereof.

I claim:

The ornamental design for a sachet or similar article, as shown.
